COMBINED TABLE AND SEATING UNIT

Barton M. Levoy, Great Neck, N.Y., assignor to Tura,
Inc., Great Neck, N.Y., a corporation of New York

Filed Sept. 27, 1963, Ser. No. 76,772

Term of patent 14 years

(Cl. D15—1)

FIG. 1

FIG. 2

Des. 199,976

PAGE 2

FIG. 3

FIG. 4

FIG. 5

FIG. 6

FIG. 1 is a perspective view showing a combined table and seating unit embodying my design;

FIG. 2 is a plan view;

FIG. 3 is an elevational view looking from the side opposite that shown in FIG. 1;

FIG. 4 is a bottom view;

FIG. 5 is an elevational view looking from the right of FIGS. 1 and 2; and

FIG. 6 is an elevational view looking from the left of FIGS. 1 and 2.

I claim:

The ornamental design for a combined table and seating unit, substantially as shown.
